UNITED STATES PATENT OFFICE.

IRVING MELCHER, OF MINNEAPOLIS, MINNESOTA.

GRAIN-TIGHT CLOSURE FOR BOX-CARS.

1,252,603.

Specification of Letters Patent. Patented Jan. 8, 1918.

Application filed August 7, 1915. Serial No. 44,193.

To all whom it may concern:

Be it known that I, IRVING MELCHER, a subject of the Emperor of Austria, residing at Minneapolis, in the county of Hennepin 5 and State of Minnesota, have invented certain new and useful Improvements in Grain-Tight Closures for Box-Cars, of which the following is a specification.

My invention relates to grain-tight closures for box cars, and has for its object to provide, in conjunction with an ordinary box car door and opening, an auxiliary door or closure which will permit the box car to be used for grain and like substances shipped 10 in bulk, and which door may be swung aside to allow the car to be used for furniture and other commodities not requiring a tight closure.

The full objects and advantages of my invention will appear in connection with the detailed description thereof and are particularly pointed out in the claims.

In the drawings, illustrating the application of my invention in one form,—
25 Figure 1 is a side elevational view of the exterior of a portion of a box car showing the opening with my improved closure covering the same, and the regular car door drawn aside. Fig. 2 is a side elevational sectional view of a portion of the interior of a box car drawn on a smaller scale with the regular door drawn aside, and showing a member of my closure swung aside and the other member swung up to entirely free said opening. Fig. 3 is a transverse elevational sectional view of the car taken through the opening, with the lower member in place, but with all the doors raised. Fig. 4 is a fragmentary view of the parts shown in Fig. 40 3 drawn on a larger scale with the closure completely sealed. Fig. 5 is a fragmentary plan sectional view of some of the parts shown in Fig. 4 and drawn on the same scale.

45 An ordinary box car 10 is shown in the drawings, having a floor 11, a roof 12, and walls, of which wall 13 alone is shown, and which wall has an opening 42 fitted with jamb posts 14 and a jamb header or lintel 15. 50 The usual sliding door 16 with which most box cars are equipped is shown in Figs. 1, 4 and 5, and is also used in conjunction with my improved closure.

My closure, as indicated in the drawings, 55 comprises an upper member and a lower member. The lower member covers about

two-thirds of the opening and consists of a rectangular frame 17, the stiles 18 and 19 of which are of T-shaped cross section and fit up against the jamb posts 14, as best shown 60 in Fig. 5. The upper rail 20 of this frame is Z-shaped in cross section and the lower rail 21 is L-shaped, as clearly shown in Figs. 3 and 4. Frame 17 is hinged on stile 19 to one of posts 14 by hinges 22 and swings inwardly into the car to lie flat against wall 13, as shown in Fig. 2. A folding door comprising two or more leaves 23 and 24 is made to cover the aperture formed by frame 17. Leaves 23 and 24 each comprise a single 70 panel 25 in a frame constituting stiles 26 and rails 27. Leaf 23 is hinged at 28 to the rail 20 of frame 17, and also to the leaf 24 at 29. Both leaves 23 and 24 are made fast to the frame 17 by latches 30 and catches 31, 75 and leaf 24 may be locked to said frame by means of a hasp 32 and staple 33. Leaf 24 is first swung out, and both leaves 23 and 24 may be swung up and outwardly, as indicated in Fig. 3, and held in place by hooking 80 on a hook 34 fast in the rail 20 of frame 17.

The upper member of my closure comprises a single panel door 35 consisting of stiles 36 and rails 37, rabbeted to fit up against jamb posts 14, side plate 15 and the 85 rail 20 of frame 17, as clearly shown in Fig. 4. It is hinged at 38 to said side plate 15 of said box car so as to swing upward within the box car where it may be held in place with a hook 39 attached to the under part of 90 roof 12, as shown in Fig. 3. When said member is closed it may be locked to frame 17 by means of a hasp 40 and staple 41. It will be noted that the construction of the doors and frame comprising my closure are 95 of such nature that all joints, excepting the floor joint, are lapped and that the whole closure is perfectly smooth on the inside, leaving hardly any place for the material contained therein to lodge and be shaken out 100 when the car is used for other purposes.

The use of my closure is obvious. When the car is to be used for grain or the like, frame 17 is swung closed and leaves 23 and 24 are made fast thereto, and the door 35 is 105 swung up and held in place by hook 39. Grain may now be loaded into the car through the opening normally closed by door 35, and when the car is full door 35 is closed and fastened and the sliding door 16 slid in 110 place and secured to cover the whole closure and protect it from external misuse. In

unloading the grain, leaf 24 is first unfastened, and when the grain is sufficiently removed leaf 23 is also made loose and the two leaves secured in position, as shown in Fig. 3. When the car is to be used for furniture, vehicles or the like the doors are swung back and up, as shown in Fig. 2, and the regular sliding door 16 is alone used to close the opening.

10 The advantages of my invention are manifest. My closure is very simple and can be easily and cheaply constructed. It is easily operated to perform its functions, and embodies such features as are most desirable in 15 this form of device.

I claim:

- 1: In combination with the opening of a box-car, a door frame covering the lower part of said opening hinged to the jamb post and adapted to swing inwardly and lie flat against the wall of the car, and a pair of door leaves hinged to each other and to the top of the frame and adapted to swing outwardly for emptying the car.
- 20 2. In combination with the opening of a box-car, a door frame covering the lower

part of said opening hinged to the jamb post and adapted to swing inwardly and lie flat against the wall of the car, a pair of door leaves hinged to each other and to the top of the frame and adapted to swing outwardly for emptying the car, and means permitting either the lower or both of said doors to be swung out.

3. In combination with the opening of a 35 box-car, a door frame covering the lower part of said opening hinged to the jamb post and adapted to swing inwardly and lie flat against the wall of the car, a pair of door leaves hinged to each other and to the top 40 of the frame and adapted to swing outwardly for emptying the car, and means associated with the top of said frame for holding both of said doors extending outward at right angles from said frame.

45 In testimony whereof I affix my signature in presence of two witnesses.

IRVING MELCHER.

Witnesses:

VERNON R. WHITELEY,
H. A. BOWMAN.
